UNITED STATES PATENT OFFICE.

CHARLES R. NORMANDY, OF WASHINGTON, DISTRICT OF COLUMBIA, ASSIGNOR TO
CLOGARD WARDROBE COMPANY, INC., OF WASHINGTON, DISTRICT OF COLUMBIA,
A CORPORATION.

GARMENT HANGER.

Application filed October 27, 1921. Serial No. 510,814.

To all whom it may concern:

Be it known that I, CHARLES R. NORMANDY, a citizen of the United States, residing at Washington, in the District of Columbia, have invented certain new and useful Improvements in Garment Hangers, of which the following is a specification.

My garment hanger is especially designed for use in clothes bags such as is partially illustrated in my Patent 1,285,336.

Many of the garment hangers now on the market are not well adapted for use in clothes bags, because they are objectionable either from the standpoint of weight or they have too long a hook, which reduces the effective length of the bag.

The object of my invention is to provide a garment hanger which is light, rigid, and of such construction that the garment on the hanger is suspended relatively close to the top of the bag whereby long garments can be suspended in the bag without touching the bottom of the bag.

The further object of my invention is to provide such a hanger that will not collapse or bend under weight of the garment and to further provide such a hanger with an additional suspending bar upon which garments, such for instance as trousers, may be suspended.

My invention consists in a garment hanger made from a single piece of wire bent upon itself intermediate its ends to form a short, rigid hook, one end portion of the wire between said hook and its extreme end being coiled intermediate its ends to produce a spring, the wire extending beyond said coil to function as a suspending bar for a garment, having a flat eye formed at its end and disposed in a horizontal plane; the other end portion of the piece of wire being suitably formed at its end with an upwardly disposed open hook positioned within the vertical plane of the garment hanger; and with the object stated, and minor objects, my invention consists of the parts and combination of parts as will be hereinafter more fully set forth.

Figure 1 is a front elevation of a garment hanger embodying my invention, the trouser

bar being shown in open position in dotted lines.

Fig. 2 is an end view of Fig. 1.

Fig. 3 is an enlarged detail sectional view on the line 3—3, Fig. 1.

Fig. 4 is a large detail view showing a formation of the suspense hook.

My improved hanger is made from a single piece of wire which is twisted upon itself intermediate its ends at 1, and then formed into a hook as at 2. The portion 3 of the piece of wire is formed to adapt it to receive a garment and is coiled to form a spring 4. This portion of the wire is extended beyond the spring coil to form a garment bar 5, which terminates at its free end in the closed eye 6, disposed in a horizontal plane, as illustrated in the drawings.

The other end portion 7 of the wire is fashioned as is the portion 3, and is provided at its free end with an open hook 8, which opens upwardly and is disposed within the vertical plane of the garment hanger.

As will be understood from the drawings, coats and the like may be hung upon the portions 3 and 7 of the hanger, while trousers and the like may be hung from the bar 5.

The body of the hanger is sustained against bending or collapsing under the weight of the garments hung thereon by reason of the hanger arm 5, which functions as a compression member thereby maintaining the distance between the coil spring 4 and the hook 8 constant.

Another advantage of positioning the hook 8 within the vertical plane of the garment hanger is to obviate the possibility of a garment becoming entangled and snagged by the hook, the garment hanger as made according to my invention being free from all sharp, angular projections at the points of contact with the garment and in the plane in which the garment would naturally hang when suspended from the hanger.

What I claim is:

A garment hanger made from a single piece of wire twisted upon itself intermediate its ends to form a garment suspension hook, and coiled intermediate one end and

said hook to form a spring, the wire beyond the coil functioning as a trouser bar and terminating at its free end in an eye, the other free end of the wire terminating in a hook positioned within the outside dimension of the hanger and in the longitudinal vertical plane of the hanger, the eye of the trouser

bar being adapted to interlock with said hook, said bar, when engaged with the hook, serving as a compression member to maintain the ends of the garment hanger in definite spaced relation.

In testimony whereof I affix my signature.

CHARLES R. NORMANDY.
